ABRADING AND BLACKBOARD CLEANING
MACHINE

Harold A. Swan, Coronado, Calif.

Application February 2, 1938, Serial No. 188,294

8 Claims. (Cl. 51—170)

My invention relates to a machine for abrading purposes for surfacing floors or other surfaces and for cleaning blackboards or the like and the objects of my invention are:

5 First, to provide a machine of this class with a large area contact surface in accordance with the size of the machine;

Second, to provide a machine of this class in which the action of an abrasive belt is very efficient;

Third, to provide a machine of this class in which the tension of the belt is easily adjusted;

Fourth, to provide a machine of this class in which the drying pulleys for the abrasive belt 15 are in direct operative relation with the operating motor;

Fifth, to provide a machine of this class with means for picking up the waste material and dust from the abrasive belt;

20 Sixth, to provide a machine of this class with means for keeping the motor cool;

Seventh, to provide a machine of this class which is very compact, light, and efficient;

Eighth, to provide a machine of this class 25 which is easy to operate; and

Ninth, to provide a machine of this class which is very simple of construction in accordance with its efficiency.

With these and other objects in view as will appear hereinafter, my invention consists of certain novel features of construction, combination and arrangement of parts and portions as will be hereinafter described in detail and particularly set forth in the appended claims, reference being had to the accompanying drawings and to the characters of reference thereon which form a part of this application in which:

Figure 1 is a top or plan view of my machine in complete form ready for use and showing a portion broken away and in section to facilitate the illustration; Fig. 2 is a side elevational view of the machine complete; Fig. 3 is a longitudinal sectional view taken from the line 3—3 of Fig. 1; Fig. 4 is a transverse sectional view taken from the line 4—4 of Fig. 3; and Fig. 5 is a partial sectional and elevational view taken from the line 5—5 of Fig. 3.

Similar characters of reference refer to similar parts and portions throughout the several views 50 of the drawings:

The main casing 1, operating handle 2, guide handle 3, motor 4, motor main shaft 5, worm pinion 6, worm gear 7, drive pulleys 8 and 9, auxiliary pulleys 10 and 11, drive belts 12 and 13, abrasive belt 14, front pulleys 15 and 16, casing

member 17, spring plate 18, spring plate adjustment members 19, spring plate latch 20, fans 21, switch 22, electric conductor 23, intermediate casing 24, and bearing casing 25 constitute the principal parts and portions of my abrading and 5 blackboard cleaning machine.

The main casing 1 is provided with a hollow cylindrical portion 1a which is provided with outwardly extending flanged portions 1b at its lower side to form a base with a wide flat surface at 10 the lower side. Mounted in this cylindrical portion 1a is the motor field 4a with the motor armature 4b positioned therein in the conventional manner. The motor 4 is provided with a main shaft 5 which extends backwardly from said motor and secured on this shaft 5 in close proximity to the motor is a fan 21 which is a double fan provided with blade portions 21a which are relatively wide and adapted to carry the dust and debris from the machine outwardly for conducting it 20 away from the machine. It is also provided with fan blade portions 21b which serve for circulating air around the motor for keeping it cool, and the side wall of the casing member 1a is provided with an opening 1c for exit of the air from the 25 fan blade portions 21b. The blades 21a and 21b are separated by means of the web 21c which extends around a fan thus providing two separate fan portions and the casing is provided with a seal 21d so that there is provided a substantial 30 seal in the casing by means of the web 21c and the shield 21d. The shaft 5 is reduced in diameter backwardly from the fan hub 21e and is supported in ball bearing 5a which is supported in a central portion 1d of the casing 1. This 35 shaft 5 extends backwardly some distance and mounted on the end thereof is a worm pinion 6 which intermeshes with a worm gear 7 shown best in Figs. 3 and 4 of the drawings. This worm gear 7 is provided with oppositely disposed shafts 40 1a which are mounted in roller bearings 7b, which roller bearings are positioned in housings 1c which are supported by means of the main casing 1d and the intermediate casing 24 as shown best in Figs. 3 and 4 of the drawings. Secured on the 45 extended ends of the shaft 1a are the drive pulleys 8 and 9 which are provided with relatively wide flanges which extend toward each other leaving a space between them at their inner edges which is substantially filled by means in the intermediate 50 casing 24 shown best in Fig. 4 of the drawings. Positioned above the pulleys 8 and 9 and slightly forwardly thereof in a casing member 10c are the auxiliary pulleys 10 and 11 which are provided with relatively wide flange portions 10a 55

and 11a so that they come nearly together at their inner edges as shown best in Fig. 4 of the drawings. These pulleys 10 and 11 are supported upon a shaft 10b which is supported upon a journal member casing 10c which supports ball bearings 10d at its opposite end which form the journal for the shaft 10b to which the pulleys 10 and 11 are secured at its opposite ends. This journal portion 10c is provided with an extended portion 10e which substantially fills the space between the inner edges of the pulleys 10 and 11 and forms a base or support for the abrasive belt at the middle portion. This journal member 10c is supported by means of a lug 10f which is secured to a lug 24a on the casing member 24 as shown best in Fig. 4 of the drawings by means of a bolt 10d.

Mounted on the pulleys 8 and 10 is a drive belt 12. Mounted on the pulleys 9 and 11 is a drive belt 14, and positioned over these drive belts 12 and 13 and extending over the pulleys 8 to 11 inclusive and forwardly therefrom at the front and at the upper and lower sides is an abrasive belt 14 which is wide enough to cover the full width of the pulleys and extend to the outer edges of the flanges of said pulleys as shown best in Fig. 4.

The casing 1 is provided with an open mouth transverse channel 1f with a front wall 1g and a back wall 1h which is adapted to receive the dust and waste material from the surfaces which are being surfaced, and it is drawn therein by means of fan portion 21a and the dust and debris is carried forwardly along one side 1i then inwardly in a channel 1j, then passes into the air conducting portion of the fan housing, then upwardly and out through the opening 1k, all shown by arrows pointing the direction of the flow of this dust and debris.

Secured on the back angular portion of the wall 1h of the casing 1 is a handle member 2 by means of brackets 2a and 2b at its upper and lower sides respectively to which the upper and lower ends of said handle are secured so that the handle 2 is in spaced relation from the wall 1h which provides for a grip for the hand for operating the machine and shifting it from place to place while surfacing the material to be surfaced.

Spaced slightly above the cylindrical portion 1a of the casing member 1 is a forwardly extending casing portion 1r, and centrally on the front end is supported a guiding handle or knob 3 which is secured by means of a bolt 3a on a beveled portion 1m of the casing member 1, thus providing means for guiding the machine with the other hand of the operator while it is being shifted about by means of the handle 2 with the other hand. Extending upwardly from the portion 1r of the casing 1 backwardly of the knob 3 is a casing portion 1n which is provided with a cover 1o. Mounted on this cover 1o is a switch 22 for controlling the circuit to the motor 4 from any source of electrical energy which is carried to the machine through the electrical conductor 23, all as shown best in Fig. 3 of the drawings.

Secured on the front end of the portion 1a of the casing 1 is a casing member 17 which is provided with a substantially straight flat upper side 17a and secured on this flat upper surface 17a is a spring plate 18 which is substantially the width of the abrasive belt 14 which serves as a spring tension support for said belt which extends forwardly from the pulleys 10 and 11 over the upper side of the portion 1a and below the

portion 1r of the casing member 1 in the space between said member. This spring plate 18 is supported at its free lower side by means of adjustable spring members 19 which are adapted to adjust the tension and keep the abrasive belt 14 in proper tension. These members 19 are provided with an adjusting hand wheel 19a to facilitate their adjustment. This casing 17 is provided with a central journal portion 17b in which is mounted a ball bearing 17c which supports a motor shaft 5b extending from the front portion of the motor 4, thus providing a journal for the supporting shaft of the motor at the front end. In order to provide a thrust bearing and for taking up wear there is provided a spring member 17c which is regulated by a set screw 17d providing proper tension on the member 17c.

Mounted over the front end of the central portion of the casing member 17 is a spring plate latch 20 which is provided with longitudinal slots 20a to permit the shifting of said plate over the outward portion of the set screw 17c. This latch member 20 is adapted to spring over the outer side of the plate 18 when the plate 18 is sprung downwardly at its lower side and will hold said plate inwardly for removing or changing the abrasive belt 14. This abrasive belt 14 extends over pulleys 15 and 16 positioned at the lower front side of the casing 1 shown best in Fig. 5 of the drawings, which pulleys 15 and 16 are supported on shaft 15a which extends in opposite direction and the central portion of said shaft is journaled in the casing 25 and supported by means of screws 25a, all as shown best in Figs. 2, 3, and 5 of the drawings.

Mounted on the lower side of the portion 1a of the casing member 1 and the lower side of the casing member 17 is a flat felt member 26 which serves as a pad for the upper side of the abrasive belt 14 tending to hold it down into position but yieldable and is positioned between the pulleys 8 and 9 and the front pulleys 15 and 16.

The operation of my abrading and blackboard cleaning machine is substantially as follows:

An abrasive belt made of the proper grade of sandpaper or emery cloth, depending upon where it is to be used is made of the proper length to be placed over the three sets of pulleys and over the spring plate 18. The spring plate 18 is depressed at the lower side so that the latch member 20 extends up over the outer side of the same for holding it inwardly; then the belt is placed in position from the open side which is normally the right hand side of the machine; then the plate 20 is shifted downwardly and the tension members 19 regulated to give the proper tension to the abrasive belt. The electrical conductor 23 is connected with a source of electrical energy and the machine is ready for operation. By shifting the switch 22, the motor starts which causes the abrasive belt to turn over the pulleys and against the surface of the felt member 26 on the lower side; the operator with the handle 2 in one hand and the knob 3 in the other hand can then shift the machine over the surface to be treated. Inasmuch as the machine is small and light it may readily be used on vertical surfaces such as blackboards for cleaning the same or for surfacing vertical walls or horizontal walls and the refuse is taken up in the machine and passed through by reason of the fan and out through the opening 1k and may be there transferred by a hose to any place desired.

Though I have shown and described a particular construction, combination, and arrange-

ment of parts and portions, I do not wish to be limited to this particular construction, combination and arrangement, but desire to include in the scope of my invention, the construction, combination, and arrangement substantially as set forth in the appended claims.

Having thus described my invention, what I claim as new and desire to secure by Letters Patent is:

1. In an abrading machine of the class described, the combination of a hollow casing, a motor mounted therein with its axis longitudinally thereof, a drive shaft in connection with one end of said motor extending backwardly therefrom, a worm pinion on the extended end of said drive shaft, a worm gear intermeshing with said worm pinion near the lower back side of one end of said casing, a shaft for said worm gear extending in opposite directions therefrom, a drive pulley secured on each end of said shaft with the surfaces of said pulleys extending to the lower back side of said casing, driven pulleys in alignment with said drive pulleys at the upper back side of said casing, belts connecting said drive pulleys with said driven pulleys, and a single abrasive belt positioned over said belts and around said casing and contacting with said belts whereby said abrasive belt is driven by said belts.
2. In an abrading machine of the class described, the combination of a hollow casing, a motor mounted therein with its axis longitudinally thereof, a drive shaft in connection with one end of said motor extending backwardly therefrom, a worm pinion on the extended end of said drive shaft, a worm gear intermeshing with said worm pinion near the lower back side of one end of said casing, a shaft for said worm gear extending in opposite directions therefrom, a drive pulley secured on each end of said shaft with the surfaces of said pulleys extending to the lower back side of said casing, driven pulleys in alignment with said drive pulleys at the upper back side of said casing, belts connecting said drive pulleys with said driven pulleys, a single abrasive belt positioned over said belts and around said casing and contacting with said belts whereby said abrasive belt is driven by said belts, other pulleys coextensive with the width of said drive pulleys and said driven pulleys positioned on the lower front side of said casing over which said abrasive belt is supported at the front lower side of said casing.
3. In an abrading machine of the class described, the combination of a hollow casing, a motor mounted therein with its axis longitudinally thereof, a drive shaft in connection with one end of said motor extending backwardly therefrom, a worm pinion on the extended end of said drive shaft, a worm gear intermeshing with said worm pinion near the lower back side of one end of said casing, a shaft for said worm gear extending in opposite directions therefrom, a drive pulley secured on each end of said shaft with the surfaces of said pulleys extending to the lower back side of said casing, driven pulleys in alignment with said drive pulleys at the upper back side of said casing, belts connecting said drive pulleys with said driven pulleys, a single abrasive belt positioned over said belts and around said casing and contacting with said belts whereby said abrasive belt is driven by said belts, other pulleys coextensive with the width of said drive pulleys and said driven pulleys positioned on the lower front side of said casing over which said abrasive belt is supported at the front lower side of said casing.
4. In an abrading machine of the class described, the combination of a hollow casing, a motor mounted therein with its axis longitudinally thereof, a drive shaft in connection with one end of said motor extending backwardly therefrom, a worm pinion on the extended end of said drive shaft, a worm gear intermeshing with said worm pinion near the lower back side of one end of said casing, a shaft for said worm gear extending in opposite directions therefrom, a drive pulley secured on each end of said shaft with the surfaces of said pulleys extending to the lower back side of said casing, driven pulleys in alignment with said drive pulleys at the upper back side of said casing, belts connecting said drive pulleys with said driven pulleys, a single abrasive belt positioned over said belts and around said casing and contacting with said belts whereby said abrasive belt is driven by said belts, other pulleys coextensive with the width of said drive pulleys and said driven pulleys positioned on the lower front side of said casing over which said abrasive belt is supported at the front lower side of said casing, a spring tension means in engagement with the upper front side of said abrasive belt supported by said casing, and means for adjusting the tension of said abrasive belt.
5. In an abrading machine of the class described, the combination of an elongated hollow casing, a motor mounted in the front end thereof with its axis longitudinally of said casing, a shaft for said motor extending backwardly substantially centrally of said casing to near the back end thereof, a worm pinion on the extended end of said shaft, a worm gear intermeshing with said worm pinion, a shaft for said worm gear extending in opposite directions laterally of said casing, a pair of drive pulleys mounted on said shaft, one on each side of said worm gear with their surfaces extending to the back and lower side of said casing, driven pulleys positioned in the upper back side of said casing in alignment with said drive pulleys, belts connecting said pulleys, a single abrasive belt mounted tightly on said belts whereby said abrasive belt is driven, said belt extending around the outer side of said casing.
6. In an abrading machine of the class described, the combination of an elongated hollow casing, a motor mounted in the front end thereof with its axis longitudinally of said casing, a shaft for said motor extending backwardly substantially centrally of said casing to near the back end thereof, a worm pinion on the extended end of said shaft, a worm gear intermeshing with said worm pinion, a shaft for said worm gear extending in opposite directions laterally of said casing, a pair of drive pulleys mounted on said shaft, one on each side of said worm gear with their surfaces extending to the back and lower side of said casing, driven pulleys positioned in the upper back side of said casing in alignment with said drive pulleys, belts connecting said pulleys, a single abrasive belt mounted tightly on said belts whereby said abrasive belt is driven, said belt extending around the outer side of said casing, and means for supporting said abrasive belt at the front end of said casing.
7. In an abrading machine of the class de-

- scribed, the combination of an elongated hollow casing, a motor mounted in the front end thereof with its axis longitudinally of said casing, a shaft for said motor extending backwardly substantially centrally of said casing to near the back end thereof, a worm pinion on the extended end of said shaft, a worm gear intermeshing with said worm pinion, a shaft for said worm gear extending in opposite directions laterally of said casing, a pair of drive pulleys mounted on said shaft, one on each side of said worm gear with their surfaces extending to the back and lower side of said casing, driven pulleys positioned in the upper back side of said casing in alignment with said drive pulleys, belts connecting said pulleys, a single abrasive belt mounted tightly on said belts whereby said abrasive belt is driven, said belt extending around the outer side of said casing, means for supporting said abrasive belt at the front end of said casing, said casing provided with a waste material conducting channel at the back side backwardly of said drive and driven pulleys.
8. In an abrading machine of the class described, the combination of an elongated hollow

casing, a motor mounted in the front end thereof with its axis longitudinally of said casing, a shaft for said motor extending backwardly substantially centrally of said casing to near the back end thereof, a worm pinion on the extended end of said shaft, a worm gear intermeshing with said worm pinion, a shaft for said worm gear extending in opposite directions laterally of said casing, a pair of drive pulleys mounted on said shaft, one on each side of said worm gear with their surfaces extending to the back and lower side of said casing, driven pulleys positioned in the upper back side of said casing in alignment with said drive pulleys, belts connecting said pulleys, a single abrasive belt mounted tightly on said belts whereby said abrasive belt is driven, said belt extending around the outer side of said casing, means for supporting said abrasive belt at the front end of said casing, said casing provided with a waste material conducting channel at the back side backwardly of said drive and driven pulleys, and spring tension means for supporting said abrasive belt in the upper front side of said casing outwardly of said casing.

HAROLD A. SWAN.
